ENVELOPE MOISTENER AND SEALER

Hjalmer E. Forsberg, Rockford, Ill., assignor to
 Crescent Manufacturing Company, Rockford,
 Ill., a copartnership

Application October 2, 1947, Serial No. 777,492

19 Claims. (Cl. 120—6)

1

This invention relates to a new and improved envelope moistener and sealer.

I am aware that efforts have been made to provide a simple and practical form of moistening and sealing device for ready use in offices and elsewhere for the purpose stated, but those previously proposed have apparently all been subject to one serious objection or another, and as a result, there are few, if any, such devices available on the market despite the acknowledged need for something of a practical form along these lines. It is, therefore, the principal object of my invention to provide a simple, economical and practical device of the kind mentioned, and one which anyone can soon grow accustomed to using, so as to do in one operation, namely, moistening and sealing, and in a fraction of the time, what he or she was previously accustomed to doing in two operations.

Experimentation with devices of this kind showed that one of the most difficult problems to overcome was that of feeding the water to the sponge or other applicator in the correct amount, so as to supply enough, but not too much, water to moisten the glued portion of the flap without too much wetting of the back of the envelope, and possibly also depositing drops here and there. In that connection, I have found that a most satisfactory applicator is a sponge rubber body with a much less porous skin covering on the back, whereby water in the correct amount is supplied by capillary attraction through the porous main body portion while wetting the back only to a small extent. This construction is of advantage not only from the standpoint of proper moistening of the envelope flap and less moistening of the back of the envelope, but is of further advantage in reducing evaporation of water through the sponge applicator. Also, the degree of compression of the sponge-rubber is enough to suitably restrict the flow of water to supply only enough but not too much water to the outer end of the sponge which wets the glued side of the envelope flap.

Another problem in the design and construction of a device of the kind mentioned is to moisten the flap while holding it at a small angle in relation to the presser blade so that the envelope will not become distorted in sealing, but will lie flat when sealed. I have found that by making the applicator sponge fairly wide and relatively thin and beveled off on the side toward the presser blade, the flap is disposed at such a small angle to the blade in the moistening of its glued inner side that there is no danger

2

of the envelope being distorted when sealed. The shape of the presser blade is also very important, because it must slide easily over the flap and yet apply pressure uniformly the entire width of the moistened glued edge portion, and I have found that if the finger of the blade is inclined inwardly toward the sponge with its end portion twisted to leave only the trailing edge portion in contact with the flap, the blade operates with least drag, and yet has sufficient bearing contact on the flap to do a good job of sealing, but if the extreme tip portion is furthermore bent forwardly, that is, toward the sponge, the operation is greatly improved. I have also found that if a light spring wire is provided to give yielding support to the trailing edge portion of the sponge rubber applicator, on that side toward the presser blade, the applicator will retain its shape indefinitely, and the efficiency of operation is furthermore greatly improved by maintaining the proper space relationship between the applicator and presser blade.

The invention is illustrated in the accompanying drawing, in which—

Fig. 1 is a front view of the envelope moistener and sealer made in accordance with my invention;

Fig. 2 is a perspective view showing the device in use in moistening and simultaneously sealing the envelope;

Fig. 3 is a sectional detail on the line 3—3 of Fig. 1, and

Fig. 4 is a perspective view of the sponge rubber applicator removed from the device.

The same reference numerals are applied to corresponding parts throughout these views.

The tubular barrel 5, which at present is made of metal but may, of course, be of a plastic or other suitable material, serves as the water reservoir and also as the operating handle for the device, and has a removable plug 6 of cork or solid rubber or any other suitable material pressed into the rear end thereof. Another similar plug 7 is pressed into the other end of the barrel, but that plug is cut in half lengthwise, as indicated at 8 in Fig. 3, to provide a space for the sponge rubber applicator 9. The latter, before entry in the barrel, appears as shown in Fig. 4, and is substantially rectangular in cross-section lengthwise and crosswise, but rounded on the outer end, as indicated at 10, and beveled off on the working face 11, as indicated at 12, toward the outer end 10 and toward the one longitudinal edge portion 13, that being the side toward the presser blade 14. The sponge 9 on that side opposite the working face 11 has a thin, slightly po-

rous skin covering 15 which is formed in the molding of the sponge rubber body in a sheet or block. In other words, the skin covering is an integral part and is shown as of perceptible thickness in Figs. 2 and 4 for purposes of better illustration. The inner end portion 16 of the sponge rubber body is arched enough to insert it into the end of the barrel 5, and the half-rounded plug 7 is then pressed into the end of the barrel alongside it, thereby compressing the sponge 9 to a semi-cylindrical cross-section throughout the length of that portion disposed in the barrel. The compression of the sponge 9 suitably restricts the seepage of water through the sponge to the exposed applicator end so that only enough but not too much water may be supplied for wetting the flap on the envelope. The bolt 17 used for fastening the bent end 18 of the arm 19 which carries the presser blade 14 is entered through a hole in the wall of the barrel 5, and has a nut 20 threaded thereon inside the barrel, and the projecting portion of the bolt 17 and the nut 20 are in that half of the barrel section receiving the sponge 9, as indicated in dotted lines in Fig. 5, so that the plug 7 can be driven into the barrel without any difficulty. The bolt 17 also serves to anchor the looped attaching end 21 of a spring wire brace 22 that is provided on one side of the end of the barrel 5 to support the projecting end of the sponge 9 against deflection laterally toward the blade 14 in the moistening of the flap of an envelope, the wire 22 being arched around the one side of the end portion of the sponge and having an inwardly bent end portion 23 which is embedded in the outer end portion of the sponge to anchor the sponge to the wire.

The presser blade 14 is formed as an integral extension of the sheet metal arm 19 and is disposed at an acute angle with respect to the longitudinal centerline of the barrel 5 so that it extends toward the applicator sponge, and its outer end portion is twisted, as indicated at 24, so as to leave the trailing edge 25 in contact with the flap 26 of the envelope 27 when the device is in operation to moisten and seal the flap of an envelope. The tip portion 28 of the presser blade is moreover bent toward the sponge 9 in the form of a slight hook and that has been found to improve the operation of the presser blade considerably. The blade 14 and arm 19 may be molded of plastic material to the form specified, and either applied to the end of the barrel or formed as an integral extension thereof.

In operation, the sponge rubber applicator is first placed with its working face 11 over the glued edge portion of the flap 26 at one end of the flap and the presser blade 14 is placed against the outer side of the end portion of the flap and the device is moved toward the other end of the flap in the direction indicated by the arrow 29 in Fig. 2, whereby to wet properly the glued side of the flap by means of the porous side of the applicator 9 while slightly wetting the back of the envelope with the skin covered side 15 slightly in advance of the presser blade 14, the blade 14 serving to press the flap down to seal the envelope in the same operation. This obviously means a saving in time because of the combination of two operations in one, and I have found that anyone, even though mechanically unskilled, can become quite proficient in the use of this device in a short time, and when once accustomed to using it, can moisten and seal envelopes in a small fraction of the time required to do it the old way where the moistening was done in one

operation, and the sealing in another operation. Furthermore, there is no danger of getting the envelope flap dirty in the event the operator's fingers are not clean at the time, and the operator does not have to get his or her hands wet. The skin covering 15 on the back of the applicator 9 reduces the extent to which the back of the envelope is moistened, only enough water being deposited there to insure quicker and better sealing. The beveled face 12 is of advantage not only in assuring wider area of contact between the applicator 9 and the glued edge portion of the flap, thus insuring wetting of the entire glued portion, as required for good sealing, but it enables keeping the flap at such a small angle with respect to the presser blade 14, that the envelope when sealed will lie flat and not show evidences of any distortion due to a twist or stress in the flap at the time of sealing. The wire 22 bracing the sponge rubber applicator 9 along its beveled edge prevents sidewise deflection of the applicator, and keeps it always in the proper spaced relationship to the presser blade 14 for most efficient operation. When the device is laid down on a desk, it is turned so that the applicator sponge is spaced from the desk top so that there is no wasting of water and no messing of the desk. If it is carelessly laid down with the applicator in contact with the desk, the skin covering 15 reduces the loss of water and the extent of wetting of the desk.

It is believed the foregoing description conveys a good understanding of the objects and advantages of my invention. The appended claims have been drawn to cover all legitimate modifications and adaptations.

I claim:

1. In an envelope moistening and sealing device comprising an elongated tubular reservoir having an open end on which is carried a presser blade extending laterally and then forwardly from the reservoir, said reservoir adapted to contain water and to be grasped as a handle for operating said device, the improvement comprising an applicator in the form of an elongated plug of compressible and resilient absorbent material one end portion of which is compressed and inserted as a closure in the open end of said reservoir, said plug projecting from the end of said reservoir and adapted to have one face of its projecting end portion wiped across the glued inner side of the flap of an envelope when the same is in folded position preparatory to being pressed down by the presser blade to seal the envelope, the compression of that end portion of said plug entered in said reservoir suitably restricting the seepage of water fed to the exposed applicator end portion from the reservoir.

2. A device as set forth in claim 1, wherein said applicator has that face thereof opposite the flap engaging face of reduced porosity so as to reduce the extent of wetting of the back of the envelope.

3. A device as set forth in claim 1, wherein said applicator is of sponge rubber and has an integral slightly porous rubber skin covering on that face opposite the flap engaging face so as to reduce the extent of wetting of the back of the envelope.

4. A device as set forth in claim 1, wherein said applicator is of sponge rubber with an integral slightly porous rubber skin covering on that face opposite the flap engaging face for the purpose described, the flap engaging face being tapered off on that side toward the presser blade for the purpose described.

5. A device as set forth in claim 1, wherein said applicator is of small thickness measured from its flap engaging face to the opposite face, and is furthermore tapered off on that side toward the presser blade for the purpose described.

6. A device as set forth in claim 1, wherein said applicator is of small thickness measured from its flap engaging face to the opposite face, and is furthermore tapered off on that side toward the presser blade for the purpose described, the tapering off of said applicator being also toward the outer end.

7. A device as set forth in claim 1, wherein said applicator is of flexible yieldable material, of the sponge rubber type, the device including a brace projecting from said reservoir alongside and engaging said applicator to resist deflection of said applicator laterally toward said pressure blade in the use of said device.

8. A device as set forth in claim 1, wherein said applicator is of flexible yieldable material, of the sponge rubber type, the device including a brace projecting from said reservoir alongside and engaging said applicator to resist deflection of said applicator laterally toward said pressure blade in the use of said device, said brace being of flexible and resilient spring wire adapted to yield under side pressure but tend to return said applicator afterward to normal position.

9. A device as set forth in claim 1, wherein said applicator is of flexible yieldable material, of the sponge rubber type, the device including a brace projecting from said reservoir alongside and engaging said applicator to resist deflection of said applicator laterally toward said pressure blade in the use of said device, said brace being of flexible and resilient spring wire adapted to yield under side pressure but tend to return said applicator afterward to normal position, the free end of said wire being bent to form an anchoring pin portion which is embedded in the material of the applicator to fasten the applicator to said brace.

10. In an envelope moistening and sealing device comprising an elongated tubular reservoir having an open end on which is carried a presser blade extending laterally and then forwardly from the reservoir, said reservoir adapted to contain water and to be grasped as a handle for operating said device, the improvement comprising a stopper plug for the open end of said reservoir that is formed so as to occupy about half of the bore of said reservoir at said end, and a compressible sponge rubber member of elongated form having one end portion inserted in said bore and compressed and retained in place in said bore by said plug, said sponge rubber member projecting from the end of said reservoir and adapted to have one face of its projecting end portion wiped across the glued inner side of the flap of an envelope to wet the same, the compression of the first end portion of said sponge-rubber member by said plug in said bore suitably restricting the seepage of water fed to the exposed applicator end portion from the reservoir.

11. In an envelope moistening and sealing device comprising an elongated tubular reservoir having an open end on which is carried a presser blade extending laterally and then forwardly from the reservoir, said reservoir adapted to contain water and to be grasped as a handle for operating said device, the improvement comprising a stopper plug for the open end of said reservoir that is formed so as to occupy about half of the bore of said reservoir at said end, a compressible sponge member of elongated form having one end portion inserted in said bore and compressed and

retained in place in said bore by said plug, said sponge-rubber member projecting from the end of said reservoir and adapted to have one face of its projecting end portion wiped across the glued inner side of the flap of an envelope to wet the same, the compression of the first end portion of said sponge-rubber member by said plug in said bore suitably restricting the seepage of water fed to the exposed applicator end portion from the reservoir, and a wire spring brace engaging the sponge on that side toward said presser blade, said brace extending lengthwise of the protruding end portion of said sponge and having one end fastened with the presser blade to said reservoir and having a hook projection on the other end embedded in the sponge to anchor the same to the brace.

12. A device as set forth in claim 10, wherein said sponge member is of sponge rubber having molded integral therewith on its back face a skin covering of less porous rubber substantially as and for the purpose described.

13. In an envelope moistening and sealing device comprising an elongated tubular reservoir having an open end on which is carried a presser blade extending laterally and then forwardly from the reservoir, said reservoir adapted to contain water and to be grasped as a handle for operating said device, said reservoir carrying a moistener element on its outer end arranged to be moistened by water fed from said reservoir, the improvement comprising a sheet metal member of L-shape having one end of one arm of the L fastened to said reservoir, the other arm of the L being disposed in laterally spaced relation to said sponge to permit passage freely therebetween of the glued edge portion of a flap on an envelope with the glued side toward said moistener, the last mentioned arm of the L being disposed at an acute angle to the longitudinal axis of the reservoir with its outer end portion closer to the moistener, and said outer end portion being twisted so that only the trailing edge portion remote from the sponge will engage the envelope flap to press it down.

14. A device as set forth in claim 13, wherein the tip portion of said twisted end portion of said arm is bent toward the sponge thereby giving a corresponding inward curvature to the outer end of the edge portion.

15. As an article of manufacture, an absorbent wiper for an envelope moistening device or the like comprising a strip of sponge rubber of generally rectangular shape and cross-section, one face of which is the wiping face, the opposite face having a rubber skin covering more or less closing the pores thereof.

16. As an article of manufacture, an absorbent wiper for an envelope moistening device or the like comprising a strip of sponge rubber of generally rectangular shape and cross-section, one face of which is the wiping face, the opposite face having a rubber skin covering more or less closing the pores thereof, one end of the wiper being tapered off toward one side edge on its wiping face.

17. As an article of manufacture, an absorbent wiper for an envelope moistening device or the like comprising a strip of sponge rubber of generally rectangular shape and cross-section, one face of which is the wiping face, the opposite face having a rubber skin covering more or less closing the pores thereof, one end portion of the wiper being tapered toward the end and toward one side edge on its wiping face.

18. In a moistening device comprising sponge-rubber liquid-applying means, the improvement comprising means for varying the size of the pores in the sponge-rubber by compression of the sponge rubber.

19. In a moistening device comprising a liquid reservoir and a sponge-rubber liquid applicator entered in an opening in said reservoir for capillary feed of water to the applicator, the improvement comprising a plug entered in the opening along-side the applicator and of such a size in relation to the dimensions of the applicator to compress the applicator to such an extent that the pores in the sponge-rubber are reduced in size to suitably restrict the capillary feed.

HJALMER E. FORSBERG.
